UNITED STATES PATENT OFFICE.

WILLIAM PAXTON BURRIS, OF SALEM, OHIO.

PENCIL-HOLDER.

SPECIFICATION forming part of Letters Patent No. 638,796, dated December 12, 1899.

Application filed May 12, 1899. Serial No. 716,514. (No model.)

To all whom it may concern:

Be it known that I, WILLIAM PAXTON BURRIS, a citizen of the United States, residing at Salem, in the county of Columbiana and State 5 of Ohio, have invented certain new and useful Improvements in Pencil-Holders, of which the following is a specification, reference being had therein to the accompanying drawing.

My invention relates to pen and pencil holders; and its primary object is to provide a device of this character which will hold pens or pencils in such a manner as to protect their points from injury and be especially adapted for use in school-rooms.

15 The novel features of the invention will be fully described hereinafter and defined in the appended claim, in connection with the accompanying drawing, which represents a view in perspective of the device.

20 The reference-numeral 1 designates a block or strip of any suitable material, preferably wood, formed on its upper surface with one or more longitudinal grooves 2 of U shape in cross-section and adapted to receive a pen or 25 pencil, as indicated by dotted lines in the drawing. While a block with a single groove (in connection with the securing means hereinafter referred to) would embody my invention, the preferred construction consists of a 30 block having a series of grooves 2 for the special purpose set forth hereinafter. Secured to the opposite edges 3 of the block 1 is a transversely-arranged plate 4, of spring metal, having a plurality of tongues 5, formed by 35 slitting the metal plate, so that one tongue will be located immediately above each of the grooves to engage the pencil resting therein.

Immediately opposite each of the tongues 5 is printed or attached a number, as "1," 40 "2," "3," &c., said consecutive numbers constituting a label or index character to identify the pencil with its owner or user.

The block or holder proper, 1, is of a length corresponding to or slightly exceeding that of 45 the usual lead-pencil or pen holder, and it is obvious that when located in its groove the pen or pencil point will be fully protected throughout its length.

The utility of the device as a school-room 50 article will be apparent from the following

statement: Ordinarily lead-pencils and pens are collected at the close of a session of school into a box provided for the purpose, and the contact of the pencil-points with the box or its contents in dropping the pencils into the 55 box frequently breaks the sharpened points or otherwise injures the pencils. It is designed by my invention to provide a holder capable of holding a sufficient number of pencils to supply one row or tier of desks in a 60 school, and by assigning a number to each pupil in the row and requiring his or her pencil to be kept in the correspondingly-numbered compartment of the holder the same pencil can be readily supplied to such pupil 65 for individual use day by day, with the result that the teacher can observe any carelessness or abuse in the use of the pencils and locate the offender by the number upon the holder, and, further, that the indiscriminate use of 70 pencils, which from a sanitary standpoint is objectionable, owing to the practice of wetting the point with the tongue, is avoided.

In practice two holders will be supplied for each row of pupils—one for pens and the other 75 for pencils.

A further advantage of the device is that when the several holders are collected and hung along the wall of the room or other convenient place the teacher in charge can tell 80 at a glance which pencils require sharpening and have such work done by the janitor or other person, so that the pencils will be in readiness for use at the next session of the school.

In case pupils are permitted to keep pens and pencils in their desks my device provides a convenient receptacle which not only protects its contents, but avoids the rattling and noise incident to the use of an ordinary 90 pencil-box.

The several spring-tongues act independently, and to insert a pencil it is pushed into the groove from right to left (in the form shown) until it is in proper engagement with 95 the spring, and to withdraw it from the holder it is pulled on through the groove to discharge it from the end of the groove opposite to that at which it is entered.

The device, as is apparent, may be cheaply 100

made, is of very durable construction, and capable of holding a pencil of any length.

I claim—

As a new article of manufacture, a pencil holder comprising a rectangular block, provided with a series of parallel grooves extending from end to end of its upper surface, and a comparatively small metal plate secured upon the block at its center, and pro-

vided with a series of integral tongues each tongue being depressed into a corresponding groove.

In testimony whereof I affix my signature in presence of two witnesses.

WILLIAM PAXTON BURRIS.
